CLAIM

I claim the ornamental design for a lighting fixture, as shown and described.

DESCRIPTION

FIG. 1 is a front elevation view of a lighting fixture showing the new design. This fixture has mirror image symmetry along a vertical imaginary plane that bisects the canopy. The shades and shade bases each have a circular horizontal cross-section.

FIG. 2 is a left side elevation view of the lighting fixture of FIG. 1, the right side elevation view being a mirror image thereof.

FIG. 3 is a bottom view of the lighting fixture of FIG. 1; and, FIG. 4 is a top view of the lighting fixture of FIG. 1. The dashed lines on the drawings depict portions of the lighting fixture that form no part of the claimed design.
